UNITED STATES PATENT OFFICE.

ARTHUR KOPPEL, OF BERLIN, GERMANY.

RAIL-FASTENING.

SPECIFICATION forming part of Letters Patent No. 749,936, dated January 19, 1904.

Application filed October 2, 1903. Serial No. 175,501. (No model.)

To all whom it may concern:

Be it known that I, ARTHUR KOPPEL, residing at Berlin, Germany, have invented certain new and useful Improvements in and Connected with Rail-Fastenings, of which the following is a full, clear, and exact specification.

My invention relates to method of and means for connecting rails to sleepers, and is more especially applicable to field-railways, the object being to provide an improved fastening which will obviate the use of separate chairs, bolts, pins, or other like small fittings, the fastenings being so effected that a reliable security against shifting and turning is attained.

According to the invention a cramp-like bending of part of a metal sleeper is utilized to hold the rail on the one side, preferably the inner side, the foot of the rail fitting under the overlapping or bent part of the cramp.

On the other side of the rail, opposite to the cramp, a tongue is bent up from the flat part of the sleeper, or the tongue may be formed from the end of the sleeper. This tongue is then bent back over the foot of the rail and

pressed, together with the inclosing part of said foot, so as to dip somewhat below the level of the top of the sleeper, forming a common depression or indentation both in rail and sleeper, and thereby effecting an intimate connection of the rail with the sleeper for the purpose of securing them against shifting and turning.

The invention is represented in the accompanying drawings, wherein—

Figures 1 to 5 are sections and plans of the new rail-fastening according to one modification of the invention.

Fig. 1 shows in elevation and section the cramp *a*, which is previously formed in the sleeper and which overlaps the foot of the rail. The left-hand view shows by dotted lines a tongue *b*, also previously formed in a manner admitting of insertion of the rail, such tongue after the rail has been placed in position being bent down onto the foot of the rail,

as shown by full lines. The tongue *b* is then firmly pressed in the middle, with the part of the foot and under part of the sleeper forming the bed for the foot, as shown in the left-hand view of Fig. 1, whereby an intimate connection is formed between the rail and the upper and lower part of the sleeper. The form of the connection is clearly illustrated in the several views, Fig. 2 being a plan on A B, Fig. 1, Fig. 4 a sectional side view on C D, Fig. 1, and Figs. 3 and 5 side views showing the cramp *a* and tongue *b*, respectively. The bending or indenting is effected in any suitable manner, but preferably by a lever jack or tool. When the lever is applied to the rail, the pressing-plate first forces the tongue *b* into position over the foot of the rail. The tongue is then firmly pressed through or indented in the middle, together with the foot of the rail and the part of the sleeper underneath. The same manner of securing is effected if the end of the flat sleeper be used as a tongue and bent over and pressed through, as before described.

Having thus described my invention, what I claim as new, and desire to secure by Letters Patent, is—

1. In combination with a rail and sleeper, a cramp formed on the sleeper engaging with the rail on one side, and a tongue bent up from the sleeper engaging the rail on the other side substantially as described.

2. In combination with a rail and sleeper, a cramp formed on the sleeper engaging the rail on one side and a tongue bent up from the sleeper engaging the rail on the other side, said tongue and that portion of the rail engaged thereby being bent down into the sleeper substantially as described.

In witness whereof I have hereunto set my hand in presence of two witnesses.

ARTHUR KOPPEL.
